(57) **CLAIM**

The ornamental design for dispenser with pads, as shown and described.

DESCRIPTION

FIG. 1 is a perspective view of an embodiment of dispenser with pads embodying our new design;
FIG. 2 is a left view thereof;
FIG. 3 is a right view thereof;
FIG. 4 is a front view thereof;
FIG. 5 is a back view thereof;
FIG. 6 is a top view thereof;
FIG. 7 is a bottom view thereof;
FIG. 8 is a perspective view of an embodiment of dispenser with pads embodying our new design;
FIG. 9 is a left view thereof;
FIG. 10 is a right view thereof;
FIG. 11 is a front view thereof;
FIG. 12 is a back view thereof;
FIG. 13 is a top view thereof; and,
FIG. 14 is a bottom view thereof.

The pads within the dispenser differ in their arrangement between views.

The broken lines shown in the drawings are for illustrative purposes only and form no part of the claimed design.

1 Claim, 8 Drawing Sheets
